UNITED STATES PATENT OFFICE

169,316

APRON

Edward H. Jones, Jr., Phoenix, Ariz.

Application September 22, 1952, Serial No. 21,548

Term of patent 14 years

(Cl. D3—26)

To all whom it may concern:

Be it known that I, Edward H. Jones, Jr., a citizen of the United States of America, residing at Phoenix, in the county of Maricopa and State of Arizona, have invented a new, original, and ornamental Design for an Apron, of which the following is a specification, reference being had to the accompanying drawing, forming a part thereof.

Figure 1 is a front elevational view of an apron, showing my new design.

Figure 2 is a rear elevational view.

Figure 3 is a sectional view taken on line 3—3 of Figure 1.

I claim:

The ornamental design for an apron, as shown.

EDWARD H. JONES, JR.
